UNITED STATES PATENT OFFICE

158,356

SOAPBOX HOLDER

Mary E. Cooney, Melbourne, Fla.

Application June 20, 1949, Serial No. 3,405

Term of patent 14 years

(Cl. D58—12.6)

To all whom it may concern:

Be it known that I, Mary E. Cooney, a citizen of the United States, residing at Melbourne, in the county of Brevard and State of Florida, have invented a new, original, and ornamental Design for a Soapbox Holder, of which the following is a specification, reference being had to the accompanying drawing, forming part thereof.

I claim:

The ornamental design for a soapbox holder, as shown.

MARY E. COONEY.
